CLAIM

The ornamental design for a combined container attachment and casing, as shown and described.

DESCRIPTION

FIG. 1 is a perspective view of a container attachment and casing illustrating my new design;

FIG. 2 is a left side elevational view of FIG. 1, the right side elevational view being identical thereto;

FIG. 3 is a front elevational view of FIG. 1, the rear elevational view being identical thereto;

FIG. 4 is a top plan view of FIG. 1; and,

FIG. 5 is a bottom plan view of FIG. 1.
